UNITED STATES PATENT OFFICE.

LOUIS J. STILLING, OF NEWARK, NEW JERSEY, ASSIGNOR OF ONE-HALF TO LOUIS ISENBURG, OF NEWARK, NEW JERSEY.

NON-REFILLABLE BOTTLE.

1,077,565.

Specification of Letters Patent.

Patented Nov. 4, 1913.

Application filed July 18, 1912. Serial No. 710,115.

To all whom it may concern:

Be it known that I, LOUIS J. STILLING, a citizen of the United States, residing at Newark, in the county of Essex and State of New Jersey, have invented certain Improvements in Non-Refillable Bottles, of which the following is a specification.

The objects of this invention are to provide an inexpensive construction of parts for a non-refillable bottle; to provide simple and efficient means for preventing the outward or inward displacement of the protecting cap; to provide an efficient valve of practicable design for construction from glass, porcelain or the like; to secure simplicity and positiveness of operation, and to obtain other advantages and results as may be brought out in the following description.

Referring to the accompanying drawings in which like numerals of reference indicate the same parts throughout the several views, Figure 1 is a central longitudinal section of a neck of a bottle with my improved closure applied thereto; Fig. 2 is a cross-sectional view on line A—A of Fig. 1; Fig. 3 is a cross-sectional view on line B—B of Fig. 1; Fig. 4 is a sectional view, in perspective, of the protecting cap forming part of the device; Fig. 5 is a perspective view of the bow spring employed in said protecting cap, and Fig. 6 is a perspective view of the valve member.

In the specific embodiment of the invention illustrated in said drawings, 1 indicates the bottle having the neck 2, the said neck being provided with a peripheral bulge 3 intermediate of the ends thereof, and the outer or upper end 4 of the neck above said bulge preferably being of greater diameter than the part thereunder. At the junction of the bottle and the neck, the material of which the same is composed is peripherally pressed inward, as at 5, whereby a valve seat 6 is provided of less diameter than the neck of said bottle. Adapted to normally seat upon said valve seat 6 is a preferably spherical or approximately spherical valve member 7, having an upwardly projecting stem 8, and said stem has at a distance from the spherical valve 7 a plurality of laterally projecting guides or arms 9, 9 adapted to loosely engage the inner surface of the neck 2 of the bottle. The stem, however, pro-

jects beyond the said guides or arms 9, 55 forming a portion hereinafter referred to as a stop 10.

The guard or cap 11 comprises essentially a collar 12 smaller than the bottle neck and having two parallel plates or partitions 13, 60 14 transversely of itself, one plate 13 forming a top and having its diameter sufficient to fill the neck of the bottle and greater than the diameter of the collar, so as to form thereby a flange 15 projecting beyond the collar at the top of the same. A space or flow passage 16 is provided between the two said plates 13, 14, and the said plates are likewise provided with openings for flow, the openings 17 in the lower plate 14 being 70 in staggered relation to the openings 18 in the upper plate 13. By such an arrangement a free passage for liquid is afforded, but the insertion of a wire or other tool in an attempt to tamper with the valve is prevented. Surrounding the said collar 12 is packing 19 of cork or other suitable packing material, compressed in assembling between said collar and the upper portion 4 of the neck. The guard or cap 11 is pressed 75 into the neck of the bottle until said packing 19 is opposite the bulge 3 of the neck, when it expands more or less into said bulge, such expansion aiding to prevent the removal of the guard or cap 11, as well as securing a tight fit in the neck. In order to positively lock the guard or cap 11 in the neck, I provide diametrically opposed apertures 20, 20 in the collar below the lower partition plate 14 and aligned apertures 21, 21 80 in the packing 19, and through these apertures project detents 22, 22 secured upon the opposite ends of a bow spring 23 normally fitting within said collar 11. By such means it will be evident that the detents 22, 90 22 may be retracted while the guard is being inserted into the bottle neck, but will spring out into the bulge 3 and act in conjunction with the packing to prevent the removal of the guard when once inserted to 100 its place.

Upon tipping the bottle to empty its contents, the valve member 7 moves away from its seat 6, but is held in approximate axial alignment therewith by the arms 9, and limited in its upward movement by the stop 10, engaging the underside of the lower plate 14. If an attempt is made to refill

the bottle, the valve will close upon its seat when the bottle is brought to approximately horizontal position, such action being facilitated by proportioning the weight of the valve to the specific gravity of the fluid so that it will not float in the said fluid but will be readily seated by attempted inflow thereof.

Having thus described the invention, what I claim is—

1. In combination with the neck of a bottle having a reduced portion forming a valve seat and having a peripheral bulge spaced at a distance above said seat, providing a peripheral shoulder adjacent said bulge between it and said seat, a packing bushing within said bulge, a collar compressing said packing against said shoulder and into said bulge, said collar having transverse spaced plates with openings, those of one plate being in staggered relation to those of the other, a valve for said valve seat between the same and said collar, and means for connecting said packing and

collar against independent movement longitudinally of the bottle neck.

2. In combination with the neck of a bottle having a reduced portion forming a valve seat of transverse means irremovable within said neck closing the direct passage thereof, a valve for said valve seat having an upwardly projecting stem integrally formed therewith and having guides projecting substantially perpendicular outwardly for sliding engagement with the neck of the bottle and an end projecting beyond said guides, whereby the valve is held in alinement with its seat and limited in its movement from the seat by the engagement of said projecting end of the stem with the said transverse means while the said guides are still below and out of contact with the same.

LOUIS J. STILLING.
